[57] **CLAIM**

The ornamental design for a printer for an electric calculator, as shown and described.

DESCRIPTION

FIG. 1 is a perspective view of a printer for an electric calculator showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a perspective view thereof;

FIG. 9 is a perspective view thereof with the cover removed; and

FIG. 10 is a central sectional view with the interior omitted for clarity.

The broken line showing of paper in FIG. 8 is for illustrative purposes only and forms no part of the claimed design.
